GEORGE A. SCHERSALO, OF NEW YORK, N. Y.

MEANS FOR PREVENTING RETROACTIVE EFFECTS IN AUDION AMPLIFIER CIRCUITS.

Application filed February 11, 1926. Serial No. 87,608.

This invention relates to the amplification of electric currents of minute intensities such as experienced in the reception of radio telephonic and telegraphic signals by means 5 of audion tubes of the three-electrode type, and more particularly to the provision of means for neutralizing, balancing, or otherwise compensating for the inherent capacity coupling between the input and output electrodes of the audion tubes of the amplifier.

It has long been known that when audion tubes are energized and the filament and grid electrodes connected to a source of alternating signal energy, and the filament and 15 plate electrodes connected to a suitable output circuit, that the variations in the output circuit are fed back into the input circuit, due to the inherent capacity coupling existing between the electrodes contained in the 20 input and output circuits. These current variations fed back into the input circuit may, and frequently do, cause oscillations which, in amplifiers, are particularly objectionable since they interfere considerably 25 with the reception of the incoming signals and frequently rise to such magnitudes as to completely incapacitate the amplifier.

In my copending applications Ser. No. 18,019, filed March 24, 1925, and Ser. No. 30 87,607, filed February 11, 1926, I have secured the desired balance between the input and output circuits by means of a network which includes a coupling between one end 35 of the input coil and a point intermediate the ends of the output inductance, the point of connection to the output inductance being predetermined to establish a ratio between the turns of the output inductance on opposite sides of the point of connection equal to 40 the inverse ratio between the inherent capacities of the audion tube. However, a balanced condition can also be obtained by a different network using a direct connection from the low potential end of the input in- 45 ductance to the plate through a suitable condenser, and arranging in this connection an inductance which is inductively coupled to the output inductance between the plate and the filament. This coupling is of such char- 50 acter that the ratio of inherent capacities between the electrodes of the audion bears a certain definite relation to the mutual in-

ductance of this coupling. The network may thus be balanced either by means of a variable condenser which changes the ratio of 55 the inherent capacities of the audion, or by varying the mutual inductance of the coupling.

In the accompanying drawings—

Fig. 1 is a diagram of a network for a single amplifier unit in which my invention is embodied in one form;

Fig. 2 is a similar view in which my invention is embodied in another form;

Figs. 3 and 4 are diagrams of further modified forms.

Referring to the drawings, particularly to Fig. 1, I have illustrated the usual audion electrodes, viz., plate 1, grid 2 and filament 3, input inductance 4 and output inductance 5. 70 The input coil 4 is connected at its high potential end directly with the grid electrode 2. At its low potential end it is connected by line 6 with the plate electrode 1 through an inductance 7 and condenser 8. The output inductance 5 is arranged in the connection 9 from the battery B to the plate 1, the negative side of the battery being connected to the filament 3. The latter is, as usual, energized by its battery A. A tuning condenser T is bridged across the input inductance 4.

The coils 5 and 7 in the output circuit have a mutual inductance. When the ratio of this mutual inductance to the self-inductance of the coil 5 is equal to the ratio of the inherent capacity between the grid and filament electrode to the sum of this capacity plus the capacity between the grid and plate electrodes, the network is balanced. In order 90 to establish this equality of ratios, I provide in the layout shown in Fig. 1 a balancing condenser 10 arranged between the plate and grid electrodes, and by means of which the capacity between these electrodes may be varied with respect to the capacity between the grid and the filament electrode. The ratio of capacities may thus be made to correspond to the ratio of mutual inductance between the coils 7 and 5 to the self-inductance of the coil 5.

Graphically stated, if the grid filament capacity (c_g) bears a certain ratio to the sum of the grid-filament capacity plus the grid-

plate capacity ($c_t + c_p$), that ratio should be equal to the ratio of the mutual inductance (M) of the coils 5 and 7 to the self-inductance (L) of the coil 5—

$$\frac{c_t}{c_t + c_p} = \frac{M}{L}$$

When this balance of ratios is established there can be no feed back of current from the output connections to the grid or input coil, and consequently there can be no oscillations set up which give rise to the objectionable squealing which occurs in an unbalanced network.

In Fig. 2 the adjustment of ratios is accomplished by varying the mutual inductance of the coils 5 and 7 instead of by varying the capacities between the electrodes, as in Fig. 1, and I have indicated this variable coupling at 11.

In order to establish a direct current path between the grid and filament electrodes of the audion, any appropriate connection may be utilized. I have illustrated in Figures 1 and 2 a connection 12 in which is interposed an appropriate high impedance 13, i. e., either a high resistance or choke coil, which will pass direct current.

In Fig. 3 I have eliminated the direct connection between the filament and grid through the high impedance 13, and have established a direct current, low voltage connection through the output coil 7 and a supplementary coil 14 which may be also inductively coupled to the coils 5 and 7. This arrangement may be somewhat more economical to construct, since the three coils 5, 7 and 14 may be wound on the same tube.

In Fig. 4 the coil 5 is replaced by a choking coil 15, and the alternating current flows now through only coil 14 instead of through both 14 and 5, as in Fig. 3.

In all the layouts the coil 7 is the balancing coil and is inductively coupled to the coil or coils in the alternating current path between the plate and filament.

It is understood that other specific networks which accomplish the same result, will readily occur to those dealing with the problem, which do not depart from what I claim as my invention.

I claim—

1. An audion amplifier network comprising an alternating current plate filament circuit including an output inductance, an input circuit between grid and plate connected to the output circuit at a point between the plate and the output inductance and including an inductance inductively coupled to the inductance in the plate filament circuit whereby to neutralize the inherent capacity of the audion electrodes, and means for preventing high direct current voltage from reaching the grid.

2. An audion amplifier net work compris-

ing an alternating current plate filament circuit including an output inductance, an input circuit between grid and plate connected to the output circuit at a point between the plate and the output inductance and including an inductance inductively coupled to the inductance in the plate filament circuit, whereby to neutralize the inherent capacity of the audion electrodes by relatively balancing the said capacities against said inductances, means for preventing high direct current voltage from reaching the grid, and means for varying the values of balanced elements of the net work.

3. An audion amplifier network comprising an alternating current plate filament circuit including an output inductance, an input circuit between grid and plate connected to the output circuit at a point between the plate and the output inductance and including an inductance inductively coupled to the inductance in the plate filament circuit whereby to neutralize the inherent capacity of the audion electrodes, and means for preventing high direct current voltage from reaching the grid, and an external adjustable condenser for varying the ratio between the inherent capacities of the plate grid and filament electrodes.

4. An audion amplifier network comprising an alternating current plate filament circuit including an output inductance, an input circuit between grid and plate connected to the output circuit at a point between the plate and the output inductance and including an input coil, one terminal of which is connected to the grid and a second coil interposed between the other end of said input coil and the plate and inductively coupled to the output inductance whereby to neutralize the inherent capacity of the audion electrodes, and means for preventing high direct current voltage from reaching the grid.

5. An audion amplifier circuit comprising plate, grid, and filament electrodes, an output coil interposed between plate and filament electrodes, an input coil, one terminal of which is connected to the grid and the other terminal of which has an alternating current connection to the plate electrode, said connection being established to a point in the output circuit between the plate and the output coil, and a balancing coil arranged in said connection between input coil and plate electrode and inductively coupled to the output coil in the plate-filament circuit whereby to neutralize the inherent capacity of the audion electrodes.

6. An audion amplifier circuit comprising plate, grid, and filament electrodes, an output coil interposed between plate and filament electrodes, an input coil, one terminal of which is connected to the grid and the other terminal of which has an alternating

current connection to the plate electrode said connection being established to a point in the output circuit between the plate and the output coil, and a balancing coil arranged in 5 said connection between input coil and plate electrode and inductively coupled to the output coil in the plate-filament circuit, together with means for varying the ratio of electrical values between related elements of the 10 network to prevent retroactive effect of the output circuit upon the input coil.

7. An audion amplifier circuit comprising plate, grid, and filament electrodes, an output coil interposed between plate and filament electrodes, an input coil, one terminal of which is connected to the grid and the other terminal of which has an alternating current connection to the plate electrode, said connection being established to a point in the 20 output circuit between the plate and the output coil, means in the said connection to prevent high direct current voltage from reaching the grid electrode, and a balancing coil arranged in said connection between input coil and plate electrode and inductively coupled to the output coil in the plate-filament circuit whereby to neutralize the inherent capacity of the audion electrodes.

8. An audion receiving system comprising an alternating current plate-filament circuit including an output inductance, an input circuit between grid and plate connected to the output circuit at a point between the plate and the output inductance, a direct current connection between grid and filament, and means for preventing retroaction of the output voltage upon the input circuit including an inductance inductively coupled to the output inductance, said inductance being a part of the input circuit.

9. An audion receiving system comprising an alternating current plate-filament circuit including an output inductance, an input circuit between grid and plate connected to the output circuit at a point between the plate and the output inductance, a direct current connection between grid and filament, means for preventing retroaction of the output voltage upon the input circuit 45 including an inductance inductively coupled to the output inductance, said inductance being a part of the input circuit, and external means for varying the ratio between the inherent capacities of the plate, grid and filament electrodes.

10. An audion receiving system comprising an alternating current plate-filament circuit including an output inductance, an input circuit between grid and plate connected to the output circuit at a point between the plate and the output inductance, a direct current connection between grid and filament, means for preventing retroaction of the output voltage upon the input circuit 55 including an inductance inductively

coupled to the output inductance, said inductance being a part of the input circuit, and an external condenser connected between the grid and a point in the plate filament circuit.

11. An electric wave receiving and amplifying system employing vacuum tubes with plate, grid, and filament electrodes, and comprising an alternating current plate-filament circuit including an output inductance, a resonant input circuit between grid and plate and connected to the output circuit between the plate and the output inductance, a direct current connection between grid and filament, and means for preventing retroaction of the output voltage upon the resonant circuit including an inductance connected in series with said resonant circuit between grid and plate, and inductively coupled to the output inductance. 70 75 80 85

12. An electric wave receiving and amplifying system employing vacuum tubes with plate, grid, and filament electrodes, and comprising an alternating current plate-filament circuit including an output inductance, a resonant input circuit between grid and plate and connected to the output circuit between the plate and the output inductance, a direct current connection between grid and filament, means for preventing retroaction of the output voltage upon the resonant circuit including an inductance connected in series with said resonant circuit between grid and plate and inductively coupled to the output inductance, and an external condenser connected between the grid and one of the other electrodes. 90 95 100

13. An electric wave receiving and amplifying system employing vacuum tubes with plates, grid, and filament electrodes, and comprising an alternating current plate-filament circuit including an output inductance, a resonant input circuit between grid and plate and connected to the output circuit between the plate and the output inductance, a direct current connection between grid and filament, means for preventing retroaction of the output voltage upon the resonant circuit including an inductance connected in series with said resonant circuit between grid and plate and inductively coupled to the output inductance, and an external condenser connected between the grid and a point of the plate-filament circuit. 105 110 115

14. An electric wave receiving and amplifying system employing vacuum tubes with plate grid and filament electrodes, and comprising an alternating current plate filament circuit including an output inductance, a resonant input circuit between grid and plate and connected to the output circuit between the plate and the output inductance, a direct current connection between grid and filament, and means for neutralizing the 120 125 130

effect of the output voltage upon said resonant input circuit, said means including an inductance connected in series with said resonant circuit between grid and plate and conductively coupled to the output inductance, and means for varying the characteristics of the inter-electrode couplings

whereby to obtain such neutralization for substantially all frequencies of the receiving range.

In testimony whereof I have signed my name to this specification.

GEORGE A. SOMERSALO.
